UNITED STATES PATENT OFFICE.

CLINTON COSTELLOE AND SHERM G. STOLL, OF HAMMOND, INDIANA.

AUTOMOBILE RADIATOR.

Application filed June 13, 1921. Serial No. 477,137.

To all whom it may concern:

Be it known that we, CLINTON COSTELLOE and SHERM G. STOLL, citizens of the United States, and residents of Hammond, in the 5 county of Lake and State of Indiana, have invented certain new and useful Improvements in Automobile Radiators, of which the following is a specification.

- Our invention relates to improvements in 10 automobile radiators, more particularly of the radiator disclosed in our Patent 1,343,352, granted June 15, 1920, and it consists in the construction, combinations and mode of assembly herein described and claimed.
- 15 One of the foremost objects of the invention is to provide a novel and simple arrangement for tightly fitting the ends of the radiator tubes into an end casting to prevent the leakage of water.
- 20 A further object of the invention is to as readily withdraw the ends of the tubes from the casting by reversing the operation of the same arrangement.

Other objects and advantages will appear 25 in the following specification, reference being had to the accompanying drawings, in which:

Figure 1 is a sectional view of the upper 30 part of the improved radiator showing the sealing plates in the neutral position,

Figure 2 is an enlarged detail sectional view of one of the radiator tubes again showing the sealing plates in the neutral position,

Figure 3 is a detail sectional view similar 35 to Figure 2, showing the sealing plates as having moved the radiator tube to the sealed position,

Figure 4 is a horizontal section on the line 4-4 of Figure 2,

Figure 5 is a plan view of the upper sealing plate, the radiator tubes being shown in section,

Figure 6 is a plan view of the lower sealing plate,

Figure 7 is a detail sectional view illustrating how the lower sealing plate is positioned to abstract the tube from the sealing position, and

Figure 8 is a detail front elevation of the 50 improved radiator, illustrating a slight modification in the form of the sealing plates and also showing radiating fins or plates

which may be used in connection with the tubes.

In producing our improved radiator, we 55 provide a plurality of radiator tubes 1 with frusto-conical ferrules 2 on the ends, for the purpose of entering the tapering recesses 3 and abutting the shoulders 4 of the top casting 5 (for example) and producing an absolutely fluid-tight and smooth-bored passage. The ferrule 2 (referring now to only one of the tubes 1) includes the enlarged body 6 with upper and lower circular flanges 7 and 8.

It is more particularly the purpose of the present invention to provide means for forcing the ferrule ends of the tubes 1 into the recesses 3 and thus produce and maintain the fluid-tight joint spoken of. The upper and 70 lower sealing plates 9 and 10 are the direct instruments by which this is accomplished. The respective plates have transverse series of pyramidal ridges 11 and 12, the apices of which approximately come in line with 75 transverse rows of the tubes 1.

The radiator tubes 1 are staggered in arrangement as can be plainly seen in Figure 5. This enables getting the tubes closer together. The pyramidal ridges occupy the 80 valleys of the respective plates 9 and 10, so that upon movement of the bottom plate 10 to the right (considering that plate as being capable of moving in a horizontal plane only) there will be an upward or vertical 85 movement of the upper plate 9, resulting in the raising of the ferrules 2 and tubes 1, by virtue of the engagement of the right sides of the pyramids 12 with the left sides of the pyramids 11.

This right movement of the bottom sealing plate 10 is produced by screwing the nut 13 down on the bolt 14 which projects from the flange 15 of the sealing plate through the vertical slot 16 in the end bridge 17. The 95 left end of the sealing plate is unsupported, that is to say by means equivalent to the bolt 14, but is kept from drooping by lateral angle plates 18, shown in connection with the modified construction of sealing plates in 100 Figure 8.

A bolt 19, projecting through a slot 20 from a flange 21 at the left end of the upper sealing plate 9 is for a purpose similar to

that of the bolt and nut 14—13, although the bolt 19 is for the purpose of abstracting the ferrules 2 from rather than forcing them into the recesses 3. The slot 20, vertical like the slot 16, is formed in the left end bridge 22, similar to the right end bridge 17 mentioned before. The bridges are secured between top and bottom castings of the radiator of which the top casting 5 only is illustrated. The end bridges are divided as shown in Figure 1, the upper portion having an inwardly bent tongue 22^a with a slot 22^b through which, and an opening in the lowermost section, one or more bolts 22^c are fastened to enable longitudinal adjustment of the end bridges when the plates 9 and 10 at the top and bottom are operated to seat the ferrules 2 in the conical recesses 3. Recourse may be had to our patent mentioned above or our co-pending application #2, for detailed illustration of the whole radiator structure.

There is a neutral and an operative position of the sealing plates 9—10. When in the neutral positions as in Figures 1, 2 and 5, the larger ones 23 of the vary-sized openings in the plate 9 coincide with the flanges 7—8 of the enlarged bodies 6. Similarly, the enlarged portions 24 of vary-sized openings in the bottom plate 10, coincide with the flanges 7—8 of the bodies 6, but as shown in Figure 6, the enlarged openings 24 are a little longer than the openings 23 in the upper plate, this for the purpose of accommodating the right movement of the plate 10 when the sealing operation is begun. The obvious purpose of providing this coincident arrangement of the sealing plates is, to enable moving the tubes up and down to properly seat the ferrules 2 in the recesses 3.

It is necessary to first move the upper plate 9 toward the left in order to get the smaller portion 25 of the openings in the plate around the bodies 6 of the ferrules beneath the upper flanges 7. These flanges thus engage the upper surface of the top plate. The necessary left movement of the top plate is gotten by screwing the bolt 19 toward the right. The part that would correspond to the nut of the bolt is brazed or otherwise affixed to the flange 21 of the top plate.

Assuming the smaller openings 25 of the top plate to be seated around the bodies 6 as in Figure 3, the nut 13 of the bolt 14 at the right is next manipulated so as to convey the bottom sealing plate 10 toward the right, causing the right side of the pyramidal ridges to ride against the left side of corresponding ridges on the top plate, thereby causing the upward movement of the top plate until a position of all of the ferrules 2, corresponding to that of the ferrules 2 in

Figure 3, is reached. Any tendency toward component downward movement of the plate 10 is resisted by the angle plates upon which it rides.

In abstracting the ferrules from the conical recesses, the reverse operation takes place. The sealing plates are moved high enough to enable setting the smaller portions 26 of the vary-sized openings in the bottom sealing plate 10, around the enlarged bodies 6 but above the bottom flanges 8, as shown in Figure 7. The bolt 19 of the upper sealing plate 9, now becomes the instrument for forcing the bottom sealing plate down, and this is accomplished by turning the bolt so as to convey the upper sealing plate toward the left. When this is done, the left sides of the pyramidal ridges 11 bear against the right sides of corresponding ridges 12 on the lower sealing plate, thus producing a downward movement of the latter plate and the consequent removal of the ferrules from the recesses 3.

When the sealing plates are raised into the position in Figure 7, the upper end of the slot 20 prevents the rising of the upper sealing plate 9 when the bolt 19 is turned, and thus that plate is set in a substantially horizontal position from which it is immovable when pressing the lower sealing plate down. In the modification in Figure 8, the upper and lower sealing plates 9^a and 10^a are for a purpose identical with that of the sealing plates 9—10 for example in Figure 2.

The only difference is one of construction, and in the modification, instead of the companion faces of the sealing plates being formed in traverse pyramidal ridges, they are provided with transverse ridges 11^a—12^a of a saw-toothed shape in cross section. Bolts 14^a and 19^a, respectively at the right and left of the radiator, are for the same purposes as before, namely, to move either one of the sealing plates for forcing the ferrules in or abstracting them from the recesses.

While the construction and arrangement of the improved radiator, or more particularly its means for fastening the radiator tubes in a casting, as herein described and claimed, is that of a generally preferred form, obviously modifications and changes may be made without departing from the spirit of the invention or the scope of the claims.

We claim:

1. In a radiator, a tube, a casting with a bore for receiving the tube, and means permanently embodied as a part of the radiator, movable in a direction transverse to the axis of the tube to force the tube-end into the bore.
2. In a radiator, a tube, a casting with a bore for receiving the tube, means perma-

- nently embodied as a part of the radiator, movable in one direction to force the tube-end into the bore, and companion means movable in the opposite direction for abstracting the tube-end from the bore. 65
3. In a radiator, a tube with a frusto-conical ferrule, a casting with a bore having a corresponding recess, means in engagement with a portion outside of the ferrule, 70
- 10 and companion means movable transversely of the axis of the tube against said engaging means to produce a wedge-action for forcing the ferrule into said recess to produce a smooth, water-tight joint. 75
- 15 4. In a radiator, a tube with a frusto-conical ferrule, a casting having a bore with a recess for receiving the ferrule, a sealing plate having a vary-sized opening positionable either to enable fitting of the ferrule in 80
- 20 the recess or assume a grip against a portion of the ferrule, means beneath the plate forming part of a wedge, and a companion sealing plate with a companion vary-sized opening for similar purposes, having wedge 85
- 25 means acting against that of the plate above for forcing the ferrule into the recess. 90
5. In a radiator, a tube with a frusto-conical ferrule, a casting having a bore with a recess for receiving the ferrule, a sealing plate having a vary-sized opening positionable either to enable fitting of the ferrule in 95
- 30 the recess or assume a grip against a portion of the ferrule, means beneath the plate forming part of a wedge, a companion sealing plate with similar vary-sized openings, having wedge means coacting with that of the plate above; and means for moving one plate in respect to the other for producing an axial shifting of the tube. 100
- 40 6. The combination of a tube, a casting having a bore for receiving the end of the tube, and means having engagement with the tube and provided with wedge elements to drive the end of the tube into said bore 105
- 45 upon movement of said means transversely of the axis of the tube. 110
7. In a radiator, a plurality of tubes, a casting having bores corresponding to the tubes, a pair of sealing plates associated 115
- 50 with the tubes having confronting wedge surfaces, means for moving one of the sealing plates in one direction to cause the other sealing plate to drive the ends of the tubes into said bores, and means for moving said 120
- 55 other sealing plate in the opposite direction to cause the first sealing plate to abstract the tubes from the bores. 125
8. In a radiator, a tube, a pair of protruding portions on the tube, a casting having a bore corresponding to the tube, a pair of sealing plates of which one is adapted to engage one protruding portion and the other is adapted to engage the other protruding portion, wedge devices on the confronting
- faces of the sealing plates, means to move one sealing plate in one direction while the other sealing plate is in engagement with its protruding portion to drive the end of the tube into the bore, and means to move the other sealing plate in the opposite direction while the first sealing plate is in engagement with its protruding portion to abstract the tube from the bore. 65
9. In a radiator, a tube having a pair of flanges, a casting having a bore corresponding to the tube, a pair of sealing plates of which one is adapted to engage the upper flange and the other is adapted to engage the lower flange, wedge formations on the confronting faces of the sealing plates, means to move one sealing plate in one direction while the other sealing plate is in engagement with the upper flange to drive the end of the tube into the bore, and means to move the other sealing plate in the opposite direction while the first sealing plate is in engagement with the lower flange to abstract the tube from the bore. 75
10. In a radiator, a tube having a pair of flanges, a casting having a bore corresponding to the tube, a sealing plate adapted to engage the upper flange, another sealing plate adapted to engage the lower flange, engaging wedge means on the confronting faces of said sealing plates, means in connection with one end of the lower sealing plate, the other end of which is free, for moving it in one direction while the other plate engages the upper flange to drive the end of the tube into the bore, means in connection with the opposite end of the upper sealing plate, the other end being free, movable in the opposite direction while the lower plate is in engagement with the lower flange to abstract the tube from the bore, and means acting as a support beneath the lower sealing plate keeping it in place by virtue of said free end. 90
11. In a radiator, a tube having a flange, a casting having a bore corresponding with the tube, a sealing plate having an opening sufficiently large to let the flange pass through and a communicating opening of a size to snugly fit the tube at the base of the flange, a companion sealing plate, wedge formations on the confronting faces of the plates, and means to move the companion sealing plate so as to exert a wedge action on the upper sealing plate and force the end of the tube into the bore. 110
12. In combination with the casting and end bridges of a radiator, a tube having a flange, a sealing plate having a vari-sized opening of which the smaller is to fit around the tube for engagement of the plate with the flange, means by which said plate is attached at one end to an adjacent bridge, the other end of the plate being free, a com-

panion sealing plate having a vari-sized opening of which the larger part is in position to enable movement of the tube, contacting wedge means on the confronting faces of the sealing plates, means by which the lower sealing plate is attached to the other end bridge, the other end of the plate being free, said attaching means being operable to cause movement of the lower sealing plate and the elevation of the tube into an opening in the casting, and means for sustaining the sealing plates.

CLINTON COSTELLOE.
SHERM G. STOLL.
